UNITED STATES PATENT OFFICE

168,981

THERMAL BASKET

Howard M. Wilkoff, New York, N. Y.

Application March 14, 1949, Serial No. 1,385

Term of patent 14 years

(Cl. D58—4)

To all whom it may concern:

Be it known that I, Howard M. Wilkoff, a citizen of the United States, residing at New York, in the county of New York, State of New York, have invented a new, original, and ornamental Design for a Thermal Basket, of which the following is a specification, reference being had to the accompanying drawings forming part thereof.

In the drawings,

Fig. 1 is a perspective view of a thermal basket showing my new design; and

Fig. 2 is a perspective view of the basket, showing the handle thereof in non-operating position.

I claim:

The ornamental design for a thermal basket, substantially as shown.

HOWARD M. WILKOFF.
